(57) **CLAIM**

The ornamental design for an all-terrain vehicle, as shown and described.

DESCRIPTION

FIG. 1 is a top, front, and left side perspective view of an all-terrain vehicle showing our new design;
FIG. 2 is a top, rear, and right side perspective view thereof;
FIG. 3 is a left side elevation view thereof;
FIG. 4 is a right side elevation view thereof;
FIG. 5 is a top plan view thereof;
FIG. 6 is a front elevation view thereof;
FIG. 7 is a rear elevation view thereof;
FIG. 8 is a top, front, and left side perspective view of an all-terrain vehicle showing our new design in accordance to a second embodiment, of which includes an additional set of rack extenders on the front rack;
FIG. 9 is a top, rear, and right side perspective view thereof;
FIG. 10 is a left side elevation view thereof;
FIG. 11 is a right side elevation view thereof;
FIG. 12 is a top plan view thereof;
FIG. 13 is a front elevation view thereof;
FIG. 14 is a rear elevation view thereof;
FIG. 15 is a top, rear, and right side perspective view of an all-terrain vehicle showing our new design in accordance to a third embodiment, of which includes an additional set of rack extenders on the front rack;
FIG. 16 is a top, front, and left side perspective view thereof;
FIG. 17 is a left side elevation view thereof;
FIG. 18 is a right side elevation view thereof;
FIG. 19 is a top plan view thereof;
FIG. 20 is a front elevation view thereof; and,
FIG. 21 is a rear elevation view thereof.
The broken lines in the drawings illustrate portions of the all-terrain vehicle that form no part of the claimed design.

1 Claim, 21 Drawing Sheets
